UNITED STATES PATENT OFFICE.

JOHAN H. HOFF, OF CHICAGO, ILLINOIS.

DESIGN FOR A BASKET.

SPECIFICATION forming part of Design No. 27,857, dated November 16, 1897.

Application filed October 2, 1897. Serial No. 653,866. Term of patent 7 years.

To all whom it may concern:

Be it known that I, JOHAN H. HOFF, a citizen of the United States, residing at Chicago, in the county of Cook and State of Illinois, have invented and produced a new and original Design or useful shape for a Basket, of which the following, in connection with the accompanying drawings, is a full, clear, and exact specification.

10 In the said drawings, Figure 1 is a perspective view of a basket embodying my design, and Fig. 2 is a side elevation thereof.

The leading features of my design consist of a basket heart-shaped in side elevation, 15 the lower converging outlines of the heart being substantially straight and continuing downwardly at about right angles to each other from the rounded shoulders of the heart, each of which is formed with an ornamental border or outline comprising a series 20 of points A, alternating with a series of projections B B', and the handle C, rising from the intersection of the shoulders of the heart on each side of the basket.

25 Each side of the basket is provided with two of the rounded shoulders, thus making four in all, which appear as in Fig. 1, the basket being apparently composed of two pieces, shaped like Fig. 2, having their straight 30 edges D joined together and the sides thus

joined swelled apart, as in Fig. 1, to make a receptacle. These rounded shoulders are also differently tinted or colored, as clearly illustrated in Fig. 2, and each has projecting downwardly toward the straight edges D a 35 number of differently colored or tinted strips or bands, and these bands on the two appear to be interlaced, so as to form a checkered design. The ornamental borders of the rounded shoulders of the heart extend from the upper 40 ends of the straight edges D around to the crotch of the heart, and the bulbous projection B' is located at about the mid-length of each border and is of much greater dimensions than the other bulbous projections B. 45 The points A are simple triangular points, while the projections B are each composed of three curves, the center one rising above the other two.

Having thus described my invention, what 50 I claim as new therein, and desire to secure by Letters Patent, is—

The new and original design or useful shape for a basket, substantially as herein shown and described.

JOHAN H. HOFF.
